UNITED STATES PATENT OFFICE.

JAMES STERLING B. SMITH, OF BROOKLYN, NEW YORK.

CATCHUP CAP.

Application filed January 11, 1923. Serial No. 611,937.

To all whom it may concern:

Be it known that I, JAMES STERLING B. SMITH, a citizen of the United States, residing at Brooklyn, in the county of Kings and State of New York, have invented certain new and useful Improvements in Catchup Caps, of which the following is a specification.

This invention relates to catchup caps, 10 that is to say, to those caps that are particularly adapted for use for catchup containers or bottles, the object of the invention being to provide an improved cap of this kind comprising a combined sealing and reusable 15 cap.

Another object of the invention is the provision of an improved catchup cap having a long depending skirt or flange effective to seal the container at the top thereof 20 and be secured thereto adjacent to the lower edge of the long flange or skirt.

A further object of the invention is the provision of an improved catchup cap having a crimped lower edge.

25 A further object of the invention is the provision of an improved catchup cap having a reinforced or hemmed lower edge.

A further object of the invention is the provision of an improved catchup cap comprising a two-piece cap having a reinforced or hemmed lower edge provided with crimps therein and which cap is adapted to seal the bottle at the top thereof, and to be secured thereto adjacent to the lower edge 35 of the cap and relatively remote from the sealing point, whereby the cap not only seals but is capable of reuse.

In practice it has been the custom to use two caps in sealing a catchup bottle, one of 40 which seals at the top of the bottle only or to use a stopper for the bottle, and then to cover this sealing cap or stopper with a deep cap, thereby forming a cover for the sealing part of the bottle, so that when the stopper 45 is removed or the sealing cap removed, the deep cap can then be reused to preserve, as far as possible, the contents of the bottle, since the shorter sealing cap is not easily replaceable, or becomes mutilated in the 50 first removal thereof.

In other words, in practice a sealing cap having a relatively short flange or skirt is provided which is secured to the bottle adjacent to the mouth thereof. In the present 55 instance it will be observed that this improved catchup cap seals at the top, but is

secured to the bottle at a point relatively remote therefrom, or at the shoulder of the bottle, and by reason of its construction it can be readily removed by the use of a coin 60 without mutilation thereof, so that the cap can be readily reused and in the reuse thereof will effectively seal the bottle. Thus, in the present improvement one cap takes the place of two or the place of a stopper, and a deep cap, so that the present cap forms a combined sealing and reusable catchup cap adapted to seal the mouth of the bottle at the top thereof, and to be locked thereto 65 around the shoulder of the bottle, usually 70 located a considerable distance below the top of the bottle.

The present improved catchup cap is comparatively simple in construction, and effective in operation, while at the same time is 75 more durable in use, and presents a pleasing appearance. It can be readily made of tin plate of comparatively light gauge, whereby it can be sealed more easily and more efficiently on the container, since it will 80 conform more effectively to the shape of the glass finish of the container, and yet notwithstanding it can be made of lighter metal, the construction is such that it will 85 be a materially stronger cap while in the preferred form thereof, the rusting of the edge of the cap is effectively retarded, and the danger of cutting the hands prevented, while the cap can be more readily removed and replaced, and this without the use of a 90 special tool for that purpose.

Those forms of crimped caps with which I am familiar have a relatively short flange for securing the cap to the bottle adjacent to the mouth thereof, and not to the bottle 95 at the shoulder thereof located relatively remote from the mouth, and in the construction of these short crimped caps known as "crown seal caps" because they seal the bottle at the top or crown thereof, it has been necessary to make them of comparatively heavy metal so that they could be pried off without mutilating them, while the raw or free edges of these caps were not only unsanitary by reason of their liability to rust 100 due to acid, moisture and other causes, but there was always the ever-present danger of cutting the hands of the user of the cap, a serious disadvantage at all times, with a rusted cap.

110 In the present improvement, however, by the provision of a reinforced edge, the

caps can be, as stated, made of a relatively lighter metal and yet be sufficiently strong to enable them to be pried off without the mutilation thereof, while in the preferred form thereof the liability of cutting the hands is prevented, and moreover they can be readily reused to effectively reseal the bottle.

In the drawings accompanying and forming a part of this specification, Fig. 1 is a view partly in section of this improved catchup cap; Fig. 2 is a fragmentary sectional view of a modified form thereof; Fig. 3 is a side view of this improved catchup cap without the hemmed or reinforced edge.

Similar characters of reference indicate corresponding parts in the several views of the drawings.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The usual catchup bottle designated herein as 2 has a mouth 3 and relatively remote therefrom a shoulder 4. The cap in the form thereof shown herein preferably comprises a two-piece cap consisting of a top 5 and a relatively long depending flange 35 or skirt 6 interlocked as at 7 in some suitable manner with the top. In catchup caps this skirt usually has a depth at least substantially equal to one-half of the diameter of the cap. This skirt or flange is provided 40 with a series of knurls or corrugations 8, which facilitate the removal and replacing of the cap, while also strengthening or reinforcing the same, and has its lower edge bent or turned upon itself as at 9 to form a 45 hem or reinforced edge.

In the form shown in Fig. 1, the lower edge is bent inwardly, which is the preferred construction, while in Fig. 2 it is bent outwardly. In Fig. 3 the edge is not bent at all. In all forms of this cap, the lower edge is flared outwardly and is crimped there-around as at 11 and the crimped edge of the cap is compressed as at 12, usually in the first instance, by machinery around the shoulder of the bottle, thereby forming an annular locking recess conforming to the shape of the shoulder of the container and which forms a holding element to secure or lock the cap in place on the bottle, while between the mouth of the bottle and the top of the cap is located a suitable liner, which seals the cap to the bottle when the same is located thereon. While the cap can be removed in various ways, nevertheless it can 65 be easily removed by the use of a coin in-

serted under the crimped lower edge, which acts as a lever against the bottle to pry off the cap. By this construction the crimped lower edge of the cap enables the flange to be reduced or drawn in and caused to more 70 efficiently hug around the shoulder of the bottle, for it has been found in practice that without these crimps the metal will spring back or away from the bottle and interfere with the proper locking thereof. The bent 75 lower edge preferably hugs the lower portion of the cap, and is preferably crimped to correspond with the flaring lower edge of the cap and thus forms a reinforced edge, which will permit the repeated reuse 80 of a coin to pry the cap off of the bottle, while at the same time the cap will always spring into place and therefore can be readily snapped on after it has been once secured thereon around the shoulder of the bottle 85 to effectively seal the bottle at the top thereof through the medium of the usual liner or packing disk 10.

In the manufacture of this improved cap, the top is formed separately by cutting suitably sized disks from the sheet metal and the depending flange or skirt of the cap having also been formed by cutting suitable strips from the metal and bent into a cylinder and suitably seamed in any desired manner, the top and the depending flange are then seamed or interlocked in some such manner as that shown in Fig. 1. The corrugations and the outturned flaring crimped portion with the lower edge bent upon itself is then formed in the flange, although this could be done before the skirt is made into a cylinder. Upon application of the cap to a bottle and suitable pressure in the first instance, the crimped lower edge of the cap is suitably reduced to engage the shoulder of the bottle and lock the cap thereon. As this annular locking recess 12 thereafter retains its shape it will in the subsequent application of the cap lock it on the shoulder 100 of the container and consequently by the mere use of a coin the cap can be pried off without mutilation or injury thereto and reused by merely snapping it on.

I believe I am the first to provide a catchup cap having a crimped lower edge, or such a cap having a reinforcing hemmed lower edge, as by bending or turning such edge upon itself, and especially a cap of such construction made of relatively thin tin plate, wherein the advantages hereinbefore pointed out are obtained, as well as the first to provide a catchup cap which will act both as a sealing cap and as a reusable cap,—in other words a catchup cap which can be secured or locked to the bottle while effectively sealing that bottle, or a cap which seals the bottle at the top and is locked to the shoulder thereof relatively remote from the top. In short I believe I am the first to provide 115 120 125 130

- a catchup cap which will seal a catchup bottle without the necessity of using a separate stopper or sealing cap and which is readily removable by means of a coin, and is effectively replaced by merely snapping it on. In other words a catchup cap which itself both seals the bottle and is locked thereto without the necessity of an independent sealing cap or separate stopper.
10. It is to be understood that by describing in detail herein any particular form, structure, or arrangement, it is not intended to limit the invention beyond the terms of the several claims or the requirements of the prior art.
- Having thus explained the nature of my said invention and described a way of constructing and using the same, although without attempting to set forth all of the forms 20 in which it may be made, or all of the modes of its use, I claim:
1. A cap having a depending skirt having an annular shoulder receiving recess functioning as a holding element, the skirt below the recess having a crimped edge inclined outwardly whereby on the insertion of a coin the cap may be removed and thereafter snapped on.
  2. A cap having a depending skirt having an annular shoulder receiving recess functioning as a holding element, the skirt below the recess having a reinforcing crimped hemmed edge inclined outwardly whereby upon the insertion of a coin the cap may be removed and thereafter snapped on.
  3. A cap comprising a sealing top having a depending skirt having an annular shoulder receiving recess functioning as a holding element, the skirt below the recess having a reinforcing crimped hemmed edge inclined outwardly whereby upon the insertion of a coin the cap may be removed and thereafter snapped on.
  4. A catchup cap having a depending skirt having a depth at least substantially equal to one-half of its diameter and having an annular shoulder receiving recess functioning as a holding element, the skirt below the recess having a crimped hemmed edge inclined outwardly whereby upon the insertion of a coin the cap may be removed and thereafter snapped on.
  5. A catchup cap comprising a sealing top having a depending skirt having a depth at least substantially equal to one-half of its diameter and having an annular shoulder receiving recess functioning as a holding element, the skirt below the recess having a reinforcing crimped hemmed edge inclined outwardly whereby upon the insertion of a coin the cap may be removed and thereafter snapped on.
  6. A catchup cap comprising a sealing top having a depending corrugated skirt having a depth at least substantially equal to one-
- half of its diameter and having an annular shoulder receiving recess functioning as a holding element, the skirt below the recess having a reinforcing crimped hemmed edge inclined outwardly whereby upon the insertion of a coin the cap may be removed and thereafter snapped on. 70
7. A two-piece catchup cap comprising a sealing top having a depending skirt interlocked with said top and having a depth at least substantially equal to one-half the diameter of the cap and having an annular shoulder receiving recess functioning as a holding element, the skirt below the recess having a reinforcing crimped hemmed edge inclined outwardly whereby upon the insertion of a coin the cap may be removed and thereafter snapped on. 75
8. A cap comprising a sealing top, a depending skirt provided with a shoulder receiving recess conforming to the shape of the shoulder of the container and functioning as a holding element, the skirt below the holding element having a reinforcing crimped edge inclined outwardly whereby upon the insertion of a coin the cap may be removed. 80
9. A cap comprising a sealing top, a depending skirt provided with a shoulder receiving recess conforming to the shape of the shoulder of the container and functioning as a holding element, the skirt below the holding element having a reinforcing crimped hemmed edge inclined outwardly whereby upon the insertion of a coin the cap may be removed. 85
10. A catchup cap comprising a sealing top, a depending skirt having a length at least substantially equal to one-half the diameter of the cap and provided adjacent to its lower edge with an annular shoulder receiving recess shaped to conform to the shoulder of a container and functioning as a holding element, the skirt below the holding element having a reinforcing crimped hemmed edge inclined outwardly whereby upon the insertion of a coin the cap may be removed. 90
11. A metal cap comprising a top and a depending skirt having an annular shoulder receiving recess adjacent to its lower edge and conforming to the shape of the shoulder of a container, and also having below said annular recess a flaring crimped edge. 95
12. A metal cap comprising a top and a depending skirt having an annular shoulder receiving recess adjacent to its lower edge and conforming to the shape of the shoulder of a container, and also having below said annular recess a flaring crimped hemmed edge. 100
13. A sealed catchup package comprising a container having an annular shoulder spaced from the top thereof, a cap comprising a sealing top having a depending skirt 110

having an annular shoulder receiving recess substantially conforming to the shape of the shoulder of the container and functioning as a holding element, the skirt below the recess having a reinforcing crimped edge inclined outwardly whereby upon the insertion of a coin the cap may be removed and thereafter snapped on.

14. A sealed catchup package comprising
10 a container having a shoulder spaced from the top thereof, and a cap comprising a sealing top having a depending skirt having a depth at least substantially equal to one-half the diameter of the cap and having
15 an annular shoulder receiving recess substantially conforming to the shape of the shoulder of the container and functioning as a holding element, the skirt below the recess having a reinforced crimped and hemmed
20 edge inclined outwardly whereby upon the

insertion of a coin the cap may be removed and thereafter snapped on.

15. The method of making a metal cap of relatively thin sheet metal which consists in interlocking a previously formed cylinder 25 forming a skirt with a top, and forming in said skirt reinforcing corrugations, and providing said skirt with an outwardly flared crimped portion bent upon itself to form a hemmed edge, and then compressing 30 said skirt above the hemmed edge upon a container shoulder spaced from the top of the container to form in said skirt an annular shoulder receiving recess substantially conforming to the shape of the shoulder of 35 the container, and thereby locking the cap on to the container.

Signed at Brooklyn, N. Y. this 9th day of January, 1923.

JAMES STERLING B. SMITH.
